DESIGN FOR A HOUSING FOR A PERMANENT WAVING MACHINE HEAD OR SIMILAR ARTICLE

George Decker, Cleveland, Ohio, assignor to The
Realistic Permanent Wave Machine Company,
Cleveland, Ohio, a corporation of Ohio

Application January 30, 1933, Serial No. 47,050

Term of patent 7 years

To all whom it may concern:

Be it known that I, GEORGE DECKER, formerly a citizen of Germany but who have taken out my first papers to become a citizen of the United States, residing in Cleveland, in the county of Cuyahoga and State of Ohio, have invented a new, original, and ornamental Design for a Housing for a Permanent Waving Machine Head, or Similar Article, of which the following is a specification, reference being had to the accompanying drawing forming part hereof.

In the accompanying drawing:

Figure 1 is a perspective view of the housing, showing my new design; and

Figure 2 is a central transverse sectional view of the housing shown in Figure 1.

I claim:

The ornamental design for a housing for a permanent waving machine head or similar article substantially as shown.

In testimony whereof I hereunto affix my signature this 21st day of January, 1933.

GEORGE DECKER.
